[57] CLAIM

The ornamental design for a sink, substantially as shown and described.

DESCRIPTION

FIG. 1 is a top plan view of a sink showing my new design;

FIG. 2 is a front elevational view thereof;

FIG. 3 is a left side elevational view thereof, the right side being a mirror image of the side shown; and

FIG. 4 is a cross sectional view taken on line 4—4 of FIG. 2.

*Fig. 1.**Fig. 2.**Fig. 3.**Fig. 4.*
